UNITED STATES PATENT OFFICE

113,009

DESIGN FOR A MOTOR COACH

Raymond Loewy, New York, N. Y., assignor to
The Greyhound Corporation, Chicago, Ill., a corporation of Delaware

Application November 12, 1938, Serial No. 81,055

Term of patent 14 years

To all whom it may concern:

Be it known that I, Raymond Loewy, a citizen of France, residing at New York, in the county of New York and State of New York, have invented a new, original, and ornamental Design for a Motor Coach, of which the following is a specification, reference being had to the accompanying drawing forming part thereof, and in which

Fig. 1 is a perspective view showing the side and front of a motor coach embodying my design;

Fig. 2 is a perspective view of the opposite side of a motor coach showing also the front thereof; and

Fig. 3 is a rear view of a motor coach embodying my design.

The present application is a continuation in part of my application, Serial Number D. 77,121, filed May 11, 1938.

I claim:

The ornamental design for a motor coach, substantially as shown.

RAYMOND LOEWY.
